(57) **CLAIM**

The ornamental design for eyedropper positioning device, as shown and described.

DESCRIPTION

FIG. 1 is a perspective view, according to the present invention;

FIG. 2 is an alternate perspective view, according to the present invention

FIG. 3 is a view of the front, according to the present invention;

FIG. 4 is a view of the back, according to the present invention;

FIG. 5 is a view of the side, according to the present invention;

FIG. 6 is a view of another side, according to the present invention;

FIG. 7 is a view of the top side, according to the present invention; and,

FIG. 8 is a view of the bottom side, according to the present invention.
